(57) **CLAIM**

The ornamental design for an energy storage system for integrated power station, as shown and described.

DESCRIPTION

FIG. 1 is a front view of an energy storage system for an integrated power station according to a first embodiment of the present application, showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is a first perspective view thereof;

FIG. 8 is a second perspective view thereof;

FIG. 9 is an enlarged view of a portion of FIG. 3;

FIG. 10 is an enlarged view of another portion of FIG. 3;

FIG. 11 is an enlarged view of a portion of FIG. 6;

FIG. 12 is an enlarged view of a portion of FIG. 7;

FIG. 13 is an enlarged view of a portion of FIG. 8;

FIG. 14 is a front view of an energy storage system for an integrated power station according to a second embodiment of the present application, showing our new design;

FIG. 15 is a rear view thereof;

FIG. 16 is a left view thereof;

FIG. 17 is a right view thereof;

FIG. 18 is a top view thereof;

FIG. 19 is a bottom view thereof;

FIG. 20 is a first perspective view thereof;

FIG. 21 is a second perspective view thereof;

FIG. 22 is an enlarged view of FIG. 18;

FIG. 23 is an enlarged view of FIG. 19;

FIG. 24 is an enlarged view of a portion of FIG. 14;

FIG. 25 is an enlarged view of a portion of FIG. 15;

FIG. 26 is an enlarged view of a portion of FIG. 16;

FIG. 27 is an enlarged view of a portion of FIG. 17; and,

FIG. 28 is an enlarged view of a portion of FIG. 21.
